UNITED STATES PATENT OFFICE

157,835

LADDER

Gorman C. Burd, Clearwater, Fla.

Application April 16, 1948, Serial No. 145,762

Term of patent 14 years

(Cl. D15—8)

To all whom it may concern:

Be it known that I, Gorman C. Burd, a citizen of the United States, residing in Clearwater, in the county of Pinellas and State of Florida, have invented a new, original, and ornamental Design for a Ladder, of which the following is a specification, reference being had to the accompanying drawing, forming part thereof.

The figure is a perspective view of a ladder showing my new design.

I claim:

The ornamental design for a ladder, as shown.
GORMAN C. BURD.
